FRANK A. LUNDQUIST, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC SWITCHING MECHANISM.

1,253,698.

Specification of Letters Patent. Patented Jan. 15, 1918.

Application filed December 2, 1916. Serial No. 134,573.

To all whom it may concern:

Be it known that I, FRANK A. LUNDQUIST, a citizen of the United States, residing at New York, in the county of New York and 5 State of New York, have invented certain new and useful Improvements in Automatic Switching Mechanisms, of which the following is a full, clear, concise, and exact description.

10 This invention relates to automatic switches, and more particularly to automatic telephone exchange switches.

15 The object of this invention is to provide a switch in which one only of several idle trunks, that may be found simultaneously by a plurality of brushes, will be used, the remaining idle trunks found being left free to be selected by other switches. In accordance with this object, several test brushes 20 are provided for each set of line brushes. Said test brushes travel simultaneously over as many different groups of terminals, and upon contact with an idle trunk by one or more of the test brushes, the progressive 25 movement of all the test brushes is stopped and one only of the several idle trunks that may have been found will be selected and used by the set of line brushes.

30 Referring to the drawing, Figure 1 is a side elevation (partially in section) of a switch of the panel type employing this invention; Fig. 2 is a view showing in detail the arrangement of the controlling apparatus of the switch; and Fig. 3 is a sectional view on line 3—3 of Fig. 1.

35 Referring to the drawing, 1 represents a frame in which the rotatably and longitudinally movable shafts 2 and 10 are mounted. A ratchet wheel 3 is slidably mounted on the 40 shaft 2 and is arranged to be engaged by a pawl 4, controlled by an electromagnet 5 to rotate said shaft. The shaft 2 is held in its normal rotary position by means of a pin 125 engaging a stop 124 fastened to the frame 1. An escapement rack comprising teeth 6 is carried by the shaft 2, and is arranged to coöperate with an escapement pawl 7, controlled by an electromagnet 8, to 45 permit said shaft 2 to be moved downward, step by step, by a spring 9. Arms 14 are spirally arranged about the shaft 2, and serve to control the movement of the several brush carriages 12. The movement of each

carriage is controlled by a collar 13. There are ten of these brush carriages (only one 55 being completely shown as each one is of similar construction). The brush carriage, to be operated, depends on the positioning of the arms 14 on the shaft 2.

A spring 15, secured to the brush carriage 12, normally engages a catch 16 of the frame 1, and holds the carriage in its normal position. A rod 17 is mounted in the brush carriage 12, and is arranged to be moved longitudinally by the arm 14. A pin 65 18 on the rod 17 moves the spring 15 away from the catch 16 when the rod 17 is moved to the left, and allows the brush carriage to be moved downward with the shaft 2. Brushes 19, 20, 21 and 22 are attached to 70 the carriage 12, and are arranged to engage the test terminals 23 of the terminal bank 24. The terminal bank 24 is divided into four groups, each group having a brush associated therewith. Each set of terminals 75 23 is associated with a trunk (not shown) leading to another switch. These trunks may be slipped in the various groups.

Arms 25 are arranged spirally around the 80 shaft 10, and serve as stops for a brush carriage 26, slidably mounted on another shaft 11 extending parallel to the shafts 10 and 2. In the normal position of the switch an extension 36 of the brush carriage 26 engages a catch 27 of the rod 17, and prevents the 85 brush carriage from moving downward. When the rod 17 is moved longitudinally by the arm 14, and after the shaft is rotated as hereinafter will more clearly appear, the brush carriage 26 slides downward by its 90 own weight in the following manner: As soon as the topmost arm 25 moves out of engagement with extension 37, the brush carriage slides down the shaft 11 until stopped by the next arm 25, etc., until it 95 reaches a position determined in a manner hereinafter described.

A sleeve 30 is mounted on the shaft 10, and is arranged to rotate with the shaft, but not to move longitudinally therewith. A 100 cam 31 is secured to the sleeve 30, and is provided with a catch 35. Fig. 2 shows the arrangement of the apparatus around the cam 31, the apparatus being omitted from Fig. 1 to simplify the showing. A number 105 of magnets 42 are spaced about the periph-

ery of the cam, and attached to the armatures of these magnets is a set of contact springs 43 and 44. Sets of contact springs 45 and 46 are kept closed by the armatures 5 when the magnets are deenergized. The springs 43 are in a position to be engaged by the catch 35, if the corresponding magnet 42 is deenergized, and the cam 31 is rotated. The cam 31 is prevented normally 10 from being rotated by a dog 32 controlled by a magnet 47.

It is believed that the invention will best be understood by describing the operation.

When subscriber at substation A removes 15 his receiver from the hook to make a call, his line is connected in any well-known manner, as by a line finder, to the switch shown in the drawing. A circuit is thereupon closed for line relay 51 from grounded battery, left-hand winding of relay 51, conductor 50, finder brush 49, terminal 48, telephone apparatus at substation A, terminal 54, finder brush 53, conductor 52, right-hand winding of relay 51 to ground. Relay 20 51, at its armature and front contact, closes a circuit for slow-release magnet 56 from grounded battery, armature and front contact of relay 51, conductor 55, slow-release magnet 56 to ground. Magnet 56 attracts 25 its armature 57 against the action of spring 59. The attraction of the armature 57 allows holding pawl 58 to engage the teeth 3, and also moves rod 60 longitudinally, which allows the catches 61, 62 and 63 to engage 30 levers 64, 65 and 66, respectively, so that when magnet 56 is deenergized, spring 59 will return the rod 60 to its normal position, and the levers 64, 65 and 66 will move the 35 slidably mounted clutch members 67, 68 and 69 to return the switch to its normal position in a manner hereinafter described. Catches 61 and 63 are pivotally mounted 40 on the rod 60, but the catch 62 is pivotally mounted on a sleeve 101, which is slidably mounted on the rod 60. This sleeve 101 is, 45 however, moved with the rod 60, at this time, by means of a pin 126, which is fastened to the rod.

Armature 57 also closes a break-point in 50 the circuit for rotary magnet 5, so that when the calling subscriber dials and line relay 51 deenergizes, the following circuit is closed at the armature and back contact of relay 51, each time the line circuit is opened, 55 to cause the shaft 2 to be rotated the distance of one tooth of the ratchet wheel 3: Grounded battery, armature and back contact of relay 51, conductor 70, armature 57 and its front contact, conductor 71, magnet 5, conductors 72 and 73, normal rotary contact 74 to ground. Upon the first energization 60 of magnet 5, a circuit is closed for slow relay 75 from grounded battery, armature and front contact of magnet 5, conductor 76, 65 slow relay 75 to ground. Slow relay 75, at

its left-hand armature and front contact, closes a substitute circuit to ground for the one above traced, for the rotary magnet, which is broken at the normal contact 74 as soon as the shaft 2 has rotated one step. 70

After the last impulse has been sent, relay 51 remains energized, thereby deenergizing magnet 5, which, in turn, deenergizes slow relay 75, which at its right-hand armature and back contact closes a circuit for the 75 escape magnet 8 from grounded battery, springs 41 and 40, conductor 39, magnet 8, conductor 77, springs 120 and 121, conductor 38, right-hand armature and back contact of relay 75, conductor 78, rotary contact 74 in 80 its off-normal position, to ground.

The rotary movement of shaft 2 positions the arms 14 so that one of them, corresponding to the number of impulses sent, is in engagement with a rod 17, to allow the corresponding brush carriage 12 to move downward with the shaft 2 to hunt for idle trunks. Assuming that one impulse has been sent, the topmost arm 14 has moved the rod 17 longitudinally so that, as magnet 8 is energized and deenergized, the shaft 2 drops and the brush carriage 12 and the shaft 10 are moved downward with the shaft 2. The brushes 19, 20, 21 and 22 on the brush carriage 12 are thus moved over the test contacts of the bank 24. The circuit for operating magnet 8 includes springs 120 and 121, controlled by the armature 7 of said magnet, thus providing a self-interrupting circuit. 95

Assume that the brushes 20 and 21 simultaneously find idle trunks upon the first step downward of the shaft 2, and the other brushes, find busy trunks. In the circuit arrangement shown, a busy trunk has ground connected to its test terminal, and the test terminal of an idle trunk is ungrounded. Therefore, the relays 42, associated with brushes 19 and 22, will be energized, the circuit for each relay being from battery, conductor 80, relay 42, springs 110 44, 43, to the corresponding brush, which is connected to ground through the test terminal of the busy lines. These relays 42 will become energized, and their armatures will allow the springs 45 and 46 to separate. 115 Since no ground is connected to the relays 42, associated with brushes 20 and 21, their contacts 45 and 46 remain closed, so that a circuit for magnet 47 is closed from grounded battery, conductor 80, springs 45 120 and 46 of the unoperated relays 42, conductor 81, off-normal springs 83 and 84, which are closed as soon as the shaft moves down one step, conductor 82, magnet 47, springs 122 and 123, to ground. Magnet 125 47 attracts dog 32 out of the notch provided therefor in the cam 31, thus allowing shaft 10 to be rotated by spring 33. The dog separates the springs 40 and 41, thereby opening the circuit of magnet 8 which stops 130

further downward movement of the switch. The dog also separates the springs 122 and 123, which opens the circuit of magnet 47.

Since the first relay 42 is energized, its armature moves its spring 43 out of the path of catch 35 of the cam 31. When shaft 10 has rotated far enough, catch 35 engages spring 43 of the relay 42 associated with the brush 20. This spring 43 is then separated from its associate spring 44, and is pushed into the slot 85 of the cam 31. The spring is so constructed as to stop further rotation of the shaft 10 when it reaches the bottom of the slot 85. The cam 31 is connected to ground, so that when it engages the spring 43, ground is connected to the test terminal of the trunk with which the brush 20 is connected, and any other multiples thereof, to cause them to test busy.

When the shaft 10 has rotated a certain amount, the uppermost arm 25 moves out of engagement with projection 37 of brush carriage 26 to allow the carriage to move down into engagement with the next arm 25, which will now be in a position to stop it on the idle trunk. The trunk seized is connected to conductors 86 and 87, which are multiplied to brushes 110 and 111 (Fig. 3) of all the brush carriages 26 of the switch. The subscriber may now operate another switch in a similar manner, to complete the connection to the wanted subscriber.

It will be noted that the terminal with which brush 21 is in engagement will still test idle, as no ground is connected thereto, so that it may be seized by another switch to which it is multiplied.

As long as the line to substation A is in use, the line relay 51 will remain energized, as will also the slow release magnet 56. As soon, however, as the line circuit is broken at substation A by the subscriber hanging up his receiver, relay 51 deenergizes and magnet 56, after an interval, releases. The retraction of armature 57 withdraws holding pawl 58 from the rotary teeth 3, thereby permitting the shaft 2 to return to its normal rotary position under action of spring 95, where it is stopped by pin 125 on shaft 2 engaging pin 124 on frame 1.

The retraction of armature 57 also causes the catches 61 and 63 to move the levers 64 and 66 to the right, thus permitting the respective clutch members 67 and 69 on a constantly revolving shaft 93 to engage and rotate the drums 90 and 91, respectively. Catch 62 does not move the lever 65 to the right at this time on account of the catch 100 being in engagement with the sleeve 101. Drum 90 winds up the tape 94 to which is attached the shaft 2, and also the lug 96. As the shaft 2 reaches its normal vertical position, the lug 96 engages the catch 61 and moves the catch out of engagement with lever 64, which allows clutch member

67 to disengage drum 90. Shaft 2 is held in its normal vertical position by the escapement arm 7 engaging ratchet 6.

Drum 91 winds up the tape 97 which is fastened to the shaft 11. Lug 99 is fastened to the shaft 11, so that, as the shaft is raised, it engages the displaced brush carriage 26 to return it to its normal position. Another lug 98 is fastened to the tape 97, and is so arranged that when the lug 99 has returned the carriage to its normal position, it engages the catch 63 to disengage the clutch member 69 from the drum 91. The shaft is then moved down by a spring 126, until a lug 127, fastened to the shaft, engages the frame 1.

The lug 98 also engages the catch 100, which releases the sleeve 101 mounted to slide on the rod 60, so that it is moved to the right by the action of spring 102. This sleeve 101 has pivoted thereto the catch 62, which moves the lever 65 to the right and throws the clutch member 68, carrying the bevel gear 103 into engagement with the bevel gear 104 on the shaft 10, to rotate the shaft back to its normal position. When the normal position is reached, the pin 105 engages the catch 62, and disengages it from the clutch 68.

The shaft 10 and brush carriage 12 are returned to their normal vertical position by spring 109, when the release magnet 56 is de-energized to withdraw pawl 58, which results in arm 14 being disengaged from rod 17.

What is claimed is:

1. In a telephone system, in combination with groups of equivalent trunk lines, automatic switching means having line brushes and test brushes, fixed contacts for said lines in said switching means, a test contact for each line, testing means associated with said switching means including said test brushes for determining idle trunks in said groups, and means for connecting said line brushes with one of said idle trunks.

2. In a telephone system, in combination with groups of equivalent trunk lines, automatic switching means having line brushes and test brushes, fixed contacts for said lines in said switching means, a test contact for each line, testing means associated with said switching means including said test brushes, a member carrying said test brushes, a member supporting said line brushes, means for driving said test brush carrying member to cause said test brushes to test said groups simultaneously and to arrest the same when one or more idle trunks are reached, and means actuated thereby for driving said line brush supporting member to cause line brushes to engage one of said selected idle trunks.

3. In an automatic switch, a set of brushes, a plurality of sets of terminals arranged for engagement by said set of brushes, means

100

110

115

120

125

130

for testing simultaneously a plurality of said terminals, means operated when one or more sets of terminals are found idle for determining which of said terminals will be engaged by said set of brushes, and means for causing said brushes to engage said predetermined set of terminals.

4. In an automatic switch, a set of brushes, groups of sets of terminals arranged for engagement by said set of brushes, a plurality of test brushes associated with said set of brushes one for each group, said test brushes being arranged simultaneously to test terminals in different groups, means for moving said test brushes, means operated when one or more idle terminals are found for determining which of the idle terminals will be engaged by said set of brushes, and means for causing said brushes to engage said predetermined set of terminals.

5. In an automatic switch, a set of brushes, groups of sets of terminals arranged for engagement by said set of brushes, a plurality of test brushes associated with said set of brushes one for each group, said test brushes being arranged simultaneously to test terminals in each group, means for moving said test brushes, a relay associated with each of said test brushes, means controlled by said relays for selecting the group containing the set of terminals to be engaged

by said set of brushes, and means for causing said set of brushes to engage said predetermined set of terminals.

6. In an automatic switch, a set of brushes, a plurality of sets of terminals arranged for engagement by said set of brushes, a plurality of test brushes arranged simultaneously to test a plurality of said sets of terminals, a relay associated with each of said test brushes, and mechanical stopping means controlled by said relays for controlling the connection between said brushes and said sets of terminals.

7. In an automatic switch, a plurality of sets of brushes, groups of terminal sets arranged for engagement by said brushes respectively, brush selecting means for rendering one of said sets of brushes operative, means for simultaneously testing a plurality of terminal sets in the group associated with said selected sets of brushes, means for determining which of said terminal sets will be engaged by said selected set of brushes when one or more terminal sets are found idle, and means for causing said set of brushes to engage said predetermined set of terminals.

In witness whereof, I hereunto subscribe my name this 29th day of November A. D., 1916.

FRANK A. LUNDQUIST.
